UNITED STATES PATENT OFFICE.

LOUIS H. HARTMAN, OF TOLEDO, OHIO, ASSIGNOR TO THE VALVE BAG COMPANY OF AMERICA, OF TOLEDO, OHIO, A CORPORATION OF OHIO.

METHOD OF AFFIXING REINFORCING TAPE.

Application filed July 8, 1926. Serial No. 121,128.

This invention relates to a method of affixing reenforcing tape, and more particularly to the use of adhesive and sewing in the affixing of reenforcing tape.

5 For some purposes, as in closing paper bags, for example, it is desirable to sew a seam through reenforcing tape and intervening fabric, and also to have the reenforcing tape adhered to the fabric, at least part 10 of the way. It has been found that difficulties arise from attempting to sew through adhesive, particularly when attempt is made to sew at high speed. The difficulties are avoided by using an adhesive which does 15 not set quickly, and by applying the adhesive only where it is most needed, or at spaced intervals along the seam, so that the needle may be thoroughly wiped upon the uncoated fabric between the places at which 20 adhesive is applied.

In the accompanying drawings forming a part of this specification, Figure 1 is a diagrammatic view of a series of bags to which reenforcing tape is being applied by my 25 method; Fig. 2 is an enlarged section on the line 2—2 of Fig. 1, and Fig. 3 is an enlarged section on the line 3—3 of Fig. 1.

In the drawings there is shown a series 30 of bags 10 having gusset folds 11, with a valve 12 at one end of one gusset fold on each bag. The bags are shown as being reinforced at the valve end by tape 13 and at the other end by tape 14. Tape 13 is adhered to the bag by adhesive 15 at the corners of the bags, where strain is greatest, while portions 16, between the bags and 35 across the bags between the corners, are left uncoated. A needle 17 is diagrammatically shown in Fig. 1, by which a seam 18 may be sewed through the tape and the fabric to 40 which it is applied.

Tape 14 is shown as having applied thereto patches 19 of adhesive at regularly spaced intervals, leaving an uncoated space 20 between each successive patch of adhesive. In 45 this case the adhesive is applied to the tape at regular intervals, and then the tape is applied to the bag without regard to the relative location of the coated portions of the 50 tape.

It will be readily seen that, at both the top and bottom of the bag, there are uncoated stretches of material between successive patches of adhesive, so that the needle is wiped dry at very frequent intervals. In 55 this manner, difficulties otherwise flowing from the attempt to sew through adhesive are avoided, especially when a slow setting adhesive is used, or one that becomes strongly adherent only after a considerable period. 60

It will be understood that this method may be employed where adhesive is needed at spaced points only, and then is applied only where needed, or it may be employed where it is advantageous to have the adhesive at frequent intervals, without particular regard to the exact location of successive patches. It will be readily understood that other arrangements of coated and uncoated portions may be made, to suit the 70 exigencies of particular needs, within the scope of the appended claims.

What I claim is:

1. The method of affixing reenforcing tape, which consists in adhering portions of 75 the tape to the article, with uncoated portions between the portions which are adhered, and sewing a continuous seam through alternate coated and uncoated portions.

2. The method of affixing reenforcing 80 tape, which consists in adhering portions of the tape to the article, with uncoated portions between the portions which are adhered, and sewing a continuous seam through alternate coated and uncoated portions before the adhesive has set. 85

3. The method of affixing reenforcing tape to fabric, which comprises adhering portions of the tape to fabric with an adhesive which, in its unset state, has comparatively little adhesion to a needle, while leaving uncoated portions of the tape and fabric between the adhered portions, and sewing a continuous seam through alternate coated and uncoated portions of the tape 95 and fabric while the adhesive is unset.

In testimony whereof, I have hereunto signed my name to this specification.

LOUIS H. HARTMAN.
